UNITED STATES PATENT OFFICE.

WILLIAM ERASTUS WILLIAMS, OF WILMETTE, ILLINOIS.

MACHINE FOR VENDING BOXES OF MATCHES.

Application filed December 18, 1926. Serial No. 155,605.

My invention relates to vending machines for boxes of matches wherein the boxes are secured upon a tape as a carrier and this tape, loaded with matches, is wound into 5 a coil or reel making a bundle of coiled-up or reeled tape to which the boxes of matches are attached, and this bundle of matches, thus arranged, is loaded into the vending machine as a single unit in the coiled-up 10 form and then the end of the tape is trained into the mechanism of the vending machine and this mechanism is arranged to feed forward and cut off a section of a tape to which there is attached a single box of matches 15 at each interval of operation. Mechanism under the control of a coin deposited in the slot permits a single operation of the machine for the deposit of each coin, an ordinary slide or handle being employed to 20 operate the mechanism which feeds out the tape and cuts it off as desired at each operation of the machine.

The general object of the machine is to provide a compact narrow width machine 25 which will carry a large load of match boxes as compared to the vending machines heretofore used wherein as a general statement the machine carries only a few boxes of matches and at the same time occupies a 30 large frontage on the counter whereon these machines are ordinarily placed for the service of the customer. Counter space is something like lot frontage in the fact that it is the front of the counter rather than the 35 depth across it that is desired to be conserved for display purposes and thus a machine which is narrow on the face of the counter and relatively deep is more advantageous from a vending machine standpoint 40 than a machine which takes a wider frontage and a narrower depth. The present design is made to accomplish this saving of counter space together with the feature 45 that an entire charge of matches can be loaded in one operation as a single cartridge as against putting the match boxes into the vending machines one at a time as has heretofore been generally the case. A further object of the invention, relates to the mechanism involved in carrying and supporting 50 the matches and training them through the machine and cutting off the tape which carries the match boxes. These details will be more fully described herein.

55 Reference will be had to the accompany-

ing drawings in which Fig. 1 is an outside elevation of the machine on the left side of the machine.

Fig. 2 is a front elevation of the machine showing the narrow width which it occupies 60 across the counter and in the front exposed to the service of the customer using the machine.

Fig. 3 is a plan of the machine.

Fig. 4 is a plan of a piece of the tape and 65 the matches attached looking from the tape side.

Fig. 5 is a sectional elevation from the left side of the machine on line 5—5 of Fig. 17 when the vending mechanism is in position 70 ready to be operated by the purchaser.

Fig. 6 is a view on same line as that of Fig. 5 showing some of the detailed parts shown in Fig. 5 but with the operating slide extended to the position which it occupies on 75 the completion of the delivery from the machine before the parts are returned to the normal position of Fig. 5.

Fig. 7 is a sectional view on line 7—7 of Fig. 17 showing the mechanism which is involved in handling the coin slide in the operation of the machine.

Fig. 8 is a similar view to that of Fig. 7 showing the parts in a different position in the operation of the machine.

Fig. 9 is a sectional view on line 9—9 of Fig. 7.

Fig. 10 is a perspective view of the locking bolt which is actuated by the coin when the same is employed in the sale as in the ordinary devices of this kind. This locking bolt being of a peculiar shape is particularly suited for this machine.

Fig. 11 is an enlarged sectional view on line 11—11 of Fig. 17 which shows the arrangement of training the end of tape connected boxes through the machine.

Fig. 12 is a transverse sectional view on line 12—12 of Fig. 11, the position of the mechanism being that at the completion of 100 one operation when it is ready for another.

Fig. 13 is a sectional view on line 13—13 of Fig. 17 and is a similar view to that of Fig. 11 and shows the parts at an intermediate point in the operation of feeding 105 forward the tape ready for an operation of cutting off a single box.

Fig. 14 is a transverse sectional detail on line 14—14 of Fig. 13.

Fig. 15 is a similar view to that of Fig. 110

12 at the completion of the outward stroke of the slide and the cutting off of a single match box from the tape.

Fig. 16 is a transverse sectional elevation 5 on line 16—16 of Fig. 10.

Fig. 17 is a plan sectional view looking down on top of the mechanism directly underneath the cover or case of machine.

Fig. 18 is an elevation of the cutter blade 10 frame, a similar view to that of Fig. 16 but showing the cutter blade and its frame only.

Fig. 19 is a sectional view looking from the left in Fig. 11 showing a cross section of the chute way being substantially across to the 15 side of stirrup 63.

Fig. 20 is a side elevation from the right side showing the chute way connection to frame plate 88.

In the drawing 1 indicates the baseboard 20 or frame base piece; 2 indicates the back wall; 3 is the front wall of the case; 4 indicates the left wall and 5 the right wall; 6 the top or cover of the machine. The right wall 5 and the top cover 6 are detachable by 25 any suitable detachable means for the purpose of loading the machine for a further supply of matches in the form of a reel or spool of boxes bound together by a tape as previously mentioned. In the left wall of 30 the machine there is fixed a permanent spindle 7, see Fig. 5, which acts as a supporting axis for the roll or coil of boxes. This coil normally is large enough substantially 35 to fill the space on the inside of the case excepting the corners. On the inside there is provided the curved wall 8, see Fig. 5, which furnishes a bottom support for the full load, coil, or reel of matches when first placed in the machine. By support I mean the support 40 for any loose portion of the coil or reel and refer to the unwound portion or slack part of it, the main weight of the reel being carried by the spindle 7.

The arrangement of the boxes on the tape 45 is shown by Fig. 4 wherein 9 indicates the boxes and 10 the tape, the tape being pasted onto the flat sides of the boxes and being less in width than the length of the box. Matches usually vended by a machine of this 50 kind are what are known as "safety matches" in rather small boxes. The tape being narrower than the length of the box, facilitates the means of carrying the box through the machine and cutting off the tape 55 in a zone wherein the guideways for the boxes extend outside of the width of the tape which is a convenience in arrangement of mechanism of this class. The mechanism for operating the machine is condensed, as 60 it were, into an upper forward or outer corner of the machine and one of the principal features of this mechanism is a slide bar having two legs or side bars 11 substantially alike, one on each side of the machine and connected across forming, as it were, a U-shaped

hand hold piece 12, see Fig. 3. The inner ends 13 of the bars 11 see Fig. 5, are connected across by a tie piece 14 and thus this double leg slide bar is arranged to be moved by hand outward in the operation of discharging a single box of matches and automatically contracted by springs 15, see Fig. 5.

The cross piece 12 may be grasped by the operator and pulled outward as the operating means of the machine but I prefer to arrange 75 an operating handle 16 in addition to this bar, see Figs. 1, 2 and 3, mounted on a shaft 17 connected by an arm 18 to a hinge pin 19 to a lever 20 hinged at 21 to the left leg of the slide 11; thus by raising and lowering 80 the end of the lever 16, the slide 11 may be moved outward from the position shown in Fig. 5 to the position shown in Fig. 6. The purpose of this lever is to give a little more purchase and make it a little easier to operate 85 the slide 11 than were the handle holding 12 only to be used to apply the operator's fingers to pull out the slide direct. The hand lever 16 may be omitted if desired and the operation of the machine confined to the 90 use of slide 11 alone. The mechanism shown in Figs. 7-10 inclusive show the arrangement of the device used to prevent the operation of the slide 11 save only as a coin may be 95 inserted to release the movement of the slide 100 to permit it to operate the mechanism which pulls forward and cuts off the tape carrying the matches. This coin controlled mechanism consists of a coin receiving slot 22 having an aperture 23 into which the coin is deposited sidewise, drops down through an aperture 24 and comes to a rest on a fixed block 25 in the case of the machine. Fastened to the right side of the right leg of the slide 11 there is a block 26 which moves 105 with the slide and as the slide 11 is pulled outward the coin indicated by the dotted lines 27 is pushed forward onto the point 28 of the locking bolt 29.

The wall 30 of a horizontal coin slot on the further movement of the slide 11 holds the coin downward and the coin thereby pushes downward the locking bolt 29 and carries 110 with it the locking projection 31 from a shoulder 32 which is in the edge of the right 115 leg of the slide 11 and thus permits the slide to be withdrawn its full distance outward in the function of operating the mechanism which feeds forward the boxes of matches. As the coin is carried over beyond the point 120 28 of the locking bolt 29 the coin is guided by a spring finger 33 and forced to drop down a slot 34 in the side of the machine down to a coin receptacle 35 in the lower front corner 125 of the machine. A spring 36 supported by a screw 37 engages the locking bolt 29 and returns it upward to its upward position shown in Fig. 7. This coin controlled mechanism is all located on the right side of the machine in a relatively thin space outside of 130

the normal mechanism which is used to feed forward and cut off the tape. A division or secondary frame piece 38 furnishes the base to which this coin controlled mechanism is attached and narrow ribs or blocks 30 and 39 form the side walls of the chuteway or slot 34 down which the coin is passed through to the receptacle 35.

It is of common practice to arrange means for preventing the return of the slide 11 or other operating means in a coin controlled machine until a complete cycle of operation of the same has been accomplished thus guarding against a false operation of the device. This mechanism, here employed, is composed of a dog 40, see Fig. 5, on a pin 41 having an end 42 connected by a spring 43 and secured at 44 to the wall 45 being a frame wall on the left of the machine corresponding to the wall 88 on the right side. Teeth 46 in the left leg of the slide 11 are acted upon by the dog 40 so that as the slide is pulled outward it prevents a return movement until the full movement of the slide 25 is arrived at when the notch 47 allows the dog 40 to assume a vertical position in which it will allow the slide to be returned home and at the same time prevent another outward movement until the slide has arrived 30 clear home or in its final retreated position wherein the dog 40 projects into another notch 48. A similar construction is usually provided in slot machines wherein movable slides are provided.

Feeding forward the match box loaded tape is accomplished by a step by step movement under the influence of the reciprocating motion of the slide 11 which is connected to actuate a crosshead which travels in a 35 curved path sliding upon curved trackways which form a chuteway through which the tape with its load of match boxes passes through and this crosshead embraces the said chuteway and is provided at the top with 40 a series of pawls or detents which engage the corners of the match boxes and push them forward as the crosshead itself moves forward, see Figs. 11, 12 and 13. This crosshead is formed of a U-shaped frame member having a lower cross piece 49 and the 45 vertical side walls 50 in which there are secured bosses 51 on which are mounted trunnion pins 52, see Fig. 12, and these trunnion pins are engaged at intervals by the front wall 53, see Figs. 7 and 8, and the rear wall 54 of apertures in the sides 11 of the slide. The horizontal distance across this 55 aperture is made necessary in order to allow the slide to be moved backward and forward 60 sufficiently to allow the coin 27 movement sufficient to engage the block 28 before the movement of the crosshead commences, and the vertical depth of these apertures are made necessary due to the fact that the crosshead travels in a curved line while the slide

travels in a horizontal line and thus the movement of the pins 52 up and down in the said apertures allow the crosshead to travel in a curve while the slide travels in a straight line. At the top edges 55 of the 50 crosshead mounted on the cross bars 56 and studs 57 there is provided detent pawls 58 and 59 which engage the corners of the match boxes as indicated by Figs. 11 and 13. The chuteway upon which the crosshead 55 rides and through which the match boxes and tape passes is formed of angle bars 60 on the upper side and with angle bars 61 on the lower side, see Figs. 11, 12 and 19, and these bars are connected across to each other 60 at the rear through the medium of the connecting band or stirrup 62 and a like stirrup 63 in the region where the tape is severed and they are also connected together and to the front face 3 of the machine at 64. The 65 inner end of this chuteway is secured at 66 by a small bolt 67 in the top wall 6 of the machine. The match box tape with its boxes of matches is prevented from a retrograde movement by a series of detent pawls 68, 90 see Figs. 11 and 12, which are mounted upon a rod 69 secured into a curved plate 70 which is fastened to angle bars 71 which is part of the stirrup piece 63 to which the chuteway angle bars 60 and 61 are connected. The 95 other end 72 of this curved plate 70 is secured to a cross piece 73 connecting the inner curved ends 74 of the angle guide bars 61. This curved end 74 is so curved to admit the end of the match box loaded tape. A 100 coil spring 75 serves to keep the several pawls 68 snugly up against the tape of the match boxes and allows the tape to be pulled forward but not backward in a retrograde movement.

A shear blade 76 shown in a lifted or clearance position in Fig. 13 and in a downward and close position in Figs. 12, 15, and 16 cuts off the match box tape 10 whenever the boxes have been fed forward to register 110 for the delivery of a single match box which delivery takes places as indicated by the match box 77 in Fig. 15 in which position a delivery has just been made and the slide 11 has commenced to retreat for a new operation, the delivered box 77 dropping out through the orifice 78 in front face 3 of the machine, see Figs. 2 and 15.

The shear blade 76 is provided with a saw toothed cutting edge 79 and works against 120 cutting edges 80 and 81, see Fig. 15, of cross-piece of the chuteway provided to assist in cutting of the tape.

The shear blade 76 is secured by the rivets 82, see Figs. 14 and 18, passing through lugs 125 83 turned over from the body of the blade itself and the rivets passing through the upper cross member 84 of the frame in which the shear blade 76 is supported and carried in its work, this frame has downward sides 130

85 connected across by the bottom member 86 integral with the side members 85 thus making the side and bottom frame which hold the blade 76, a U-shaped piece which 5 embraces angle bars 60 and 61 of the chute-way and the edges 87 of these side frame pieces 85 abut against the edges 89 of the frame plates 45 and 88 on the sides forming a part of the frame structure of the machine.

A guide plate 90 is a continuation of the angle bars 61 carrying the chute-way into the delivery orifice 78 and connected at 65 to front face 3 and this guide plate 90 is 15 connected to the angle piece 71 before mentioned, and extending across and on top of this plate 90 there is the shear piece 80. On the bottom section 86 of this blade frame sides or legs 85 there is secured an angle 20 piece 91 which is engaged by the springs 92 running over the bar 93 between the plates 45 and 88 using this bar as a fulcrum and the other ends of these springs are secured at 94 to a block 95 secured to the front wall 25 piece 3 of the frame. Thus the springs 92 normally hold the shear blade down to the position shown in Figs. 12, 15, and 16. The frame which holds the shear blade 76 which reciprocates vertically along the edges 89 of 30 the frame pieces 88 is held in such a position by means of guide blocks 96 having lips 97 which overlap and engage projections 98 on the plates 45 and 88, see Figs. 13 and 14, and the stirrup 63 guides the lower end of 35 the side pieces 85 upon a downward movement against displacement on the edges 89 of the plates 45 and 88. Blocks 99 shown in dotted lines in Fig. 15 and in full lines in Fig. 6 guide sidewise the cutting blade frame at its lower end.

The cutting blade frame with its cutting blade is actuated by a constant pressure downward of the springs 92, but is raised by cam blocks 100, see Figs. 11, 13, 15 and 16 45 which cam blocks have the cam faces 101 adapted to engage rollers 102 mounted on pins 103, see Fig. 16, in the frame pieces 85 and the cam blocks 100 are pivoted at 104 on the slide piece 11 one of these cam blocks 50 being mounted on each side of blade frame on legs 11 of the said slide. Slots 105 in the cam blocks 100 work over pins 106 which limit the movement of the blocks to the downward position shown in Figs. 11 and 55 13. The rollers 102 travel around the cam blocks 100 so that when the slide 11 is pulled forward or outward in the function of delivering a section of tape carrying one match box, the first movement of the slide 60 after the coin is inserted serves to lift the shear blade by causing the rollers 102 to rise up the inclined surfaces 101 of the cam blocks 100 and when in upward position see Fig. 13, hold the shear blade stationary until

a completion of the stroke of the slide allows 65 the rollers 102 to drop down over the end of the cam block at the hinge pins 104 which 70 position of the slide is arrived at at the full outward stroke of the slide 11. At this point the end match box has been pushed out, touches and is held by guard pieces or 75 registering stops 107, see Fig. 13. Guard pieces 107 enter into apertures in the plate 90 and are secured to the member 86 of the cutter blade frame and register or stop the 80 end of the tape in the exact position where the cutter blade 76 projects down between the match boxes and severs the tape allowing a discharge of the match boxes as shown by 77 in Fig. 15. Then on the return of the 85 slide 11 under the control of the springs 15 as before described, see Figs. 5 and 6, the cam blocks 100 rock up over the rollers 102 as indicated by Fig. 15 and thus allow the 90 cam blocks to retreat back to a normal position, a little further back than is shown in Fig. 11 ready for another feeding action of the boxes and tape, the pawls 58 and 59 again engaging a new set of match boxes by having pawl teeth 108 and 109 engaging the 95 upper corners of the match boxes. The curved chute-way produces the gap between the boxes at the top which facilitates the entrance of the pawl teeth 108 and 109 and thus permits boxes to be set close together, or even in contact when secured to the tape, thus saving space for the storage of the 95 boxes in the machine.

I provide several of the pawls 58 and 59 in order to insure that some of them will 100 fall by gravity into engagement with the boxes and thus save accidental or misplaced action of the machine. Slide pieces 11 are cut down at their inner end, see Fig. 5, and are provided with guide slots 110 which 105 ride on pins 111 supported in the machine.

The cutter blade 76 has an aperture as indicated by 112 to allow inspection through the delivery orifice 78 in order to observe 110 whether or not a match box is in the position to be delivered at the next operation of the machine, see Figs. 15 and 16. A glass window 113 is provided in the top of the machine arranged for the purpose of seeing the supply of matches ready for delivery. 115 In the use of the machine the right side being the side 5 as indicated in Fig. 2, is taken off and a coil or reel or cartridge of matches is inserted onto the spindle 7 see Fig. 5, and the end of the tape and match 120 boxes is trained through the chute-way up to the position indicated by Fig. 11, the boxes being shoved under and over the pawls which hold the boxes in the chute-way before described. The tape being narrower than the length of the boxes permits the shear blade 76 likewise to be narrower 125 and pass between the members 61 see Fig.

16 allowing the guideway to extend out and beyond the region of the travel of the shear blade 76.

The cutter blade 76 makes a secure stop 5 against robbing the machine. As this blade is raised the guard pieces 107 come up with it thus producing a stop to prevent more than one box being discharged until the cutter blade again descends and cuts off 10 the tape free from the box which is up against the guards 107 and as the cutter blade starts to descend the guards also descend and clears the match box that is cut off and thus permits that box to fall down 15 for delivery as indicated by 77, Fig. 15.

I have disclosed novel features in this application which are also disclosed in my co-pending applications Serial Numbers 89,194 20 and 153,981 and I expressly reserve the right 20 to claim any novelty disclosed but not claimed herein in another co-pending application.

Claims:

1. In a machine of the class described, a 25 casing having a chamber adapted to hold a coil of match boxes secured together by a tape and a curved chuteway through which the boxes and tape are fed to a discharging orifice, reciprocating feeding mechanism for feeding forward the match boxes in a 30 step by step movement and provided with pawl engaging mechanism for engaging the edges of the boxes as the same are held in the curved chuteway.

2. In a machine of the class described, a 35 casing having a chamber adapted to hold a series of match boxes secured together by a tape, a curved chuteway through which the said boxes and tape are fed to a delivery 40 orifice, a feeding mechanism for feeding the boxes through the said chuteway and a reciprocating crosshead embracing the said chuteway, and sliding back and forth longitudinally thereon, and carrying a series of 45 pawls adapted to engage and push the match boxes through the chuteway, a reciprocating cutter blade mounted transversely of the said chuteway and adapted to be operated by a spring movement and the said 50 movement controlled in relation to the re-

ciprocating of the said crosshead whereby the cutter blade is made to register exactly and cut the tape holding the boxes at the exact position between the boxes on the tape.

3. In a machine of the class described, the combination with a casing having a chamber, of means for revolvably mounting a coil of flexibly connected match boxes within said chamber, a chuteway leading from said chamber through which said match boxes are withdrawn, the said chuteway being curved to provide openings between said boxes to permit the admission of severing means, a plurality of detent pawls adapted 60 to simultaneously engage said chain of match boxes, means adapted to reciprocate said pawls along said chuteway, and means adapted to sever a terminal box from said chain.

4. In a machine of the class described, the combination with a casing having a chamber adapted to hold and permit the unreeling of a coil of connected match boxes, of a curved guide for said chain of match 75 boxes to permit the admission of box severing means, a transversely reciprocating box severing means, a cam adapted to withdraw said severing means hold said means during an advance of said chain of 80 boxes and then release said means, and resilient means adapted to suddenly operate said severing means.

5. In a machine of the class described, the combination with a casing having a chamber adapted to hold a chain of flexibly connected match boxes arranged in a unit package, a chuteway leading from said chamber through which said match boxes are withdrawn, the said chuteway being curved 90 to permit the admission of severing means, reciprocating means adapted to advance said chain, severing means adapted to detach a terminal box, and a movable guard for protecting said box chain when said severing 95 means is inoperative.

Signed at Chicago, in the county of Cook and State of Illinois, this 16th day of December, 1926.

WILLIAM ERASTUS WILLIAMS.
